DISTILLATION OF MINERAL OIL

Cecil Ferdinand Slawson, Lockport, Ill., assignor
to The Texas Company, New York, N. Y., a
corporation of Delaware

Application June 23, 1934, Serial No. 732,004
Renewed March 17, 1938

13 Claims. (CL. 196—73)

This invention relates to the distillation of a composite liquid, and more particularly to the distillation of a hydrocarbon oil.

In the modern practice of petroleum distillation, it is customary to top a crude oil by flashing from a tube still heater into a fractionating tower from which gasoline vapors may be removed overhead, a kerosene distillate as a side stream cut, and heavier residuum from the base 10 of the tower. The kerosene side stream may be stripped with steam in an auxiliary or stripping tower in order to obtain a close cut. While this effectively removes lighter constituents from the kerosene cut, the stripped residue which is generally removed from the base of the auxiliary 15 tower may contain heavier fractions and impurities which necessitates redistillation or purification treatments. If it is attempted to redistill the kerosene cut within the auxiliary or stripping tower, large quantities of steam may be required 20 such as to render the process uneconomical.

It is an object of the present invention to provide a method of and apparatus for distilling hydrocarbon oil of this character, in which a side 25 stream cut from a primary fractionating tower may be effectively stripped and redistilled in an auxiliary or stripping tower, to thereby obtain a close clean distillate cut as a side stream from the stripping tower, while at the same time 30 effecting substantial economies in the operation thereof.

It is also modern practice to combine a topping unit of the character described above with a vacuum distillation unit where the heavier or 35 lubricating fractions of the oil are distilled. This is the so-called atmospheric-vacuum distillation apparatus, in which residuum from the first stage or topping unit is passed through a second stage tube still heater, where it is heated to a high temperature, and then flashed into the vacuum fractionating tower. It is known to withdraw a portion 40 of residuum which has been heated in a second stage heater, and return this heated residuum to the fractionating tower of the first stage, to supply additional heat thereto for distillation purposes. This is objectionable, as the high temperatures of the second stage tube still 45 may result in too high a heat input into the first stage fractionating zone, such that desired flexibility of control is lacking.

Another object of the present invention is to provide a two stage distillation system of this character, in which additional heat input is provided by recirculating topped crude or residuum 50 to the primary fractionating tower and/or the

stripping tower of the first stage, while affording an independent control of the heat input to secure desired flexibility of operation.

Briefly, my invention contemplates withdrawing a portion of the reduced crude or residuum of the first stage, passing it through a separate heating coil where independent control of temperature is afforded, and introducing heated residuum into the lower portion of the stripping tower to supply the necessary heat for redistillation and 10 stripping therein, thereby obviating the use of objectionable quantities of steam for this purpose. This may be accomplished by withdrawing a portion of the residuum passing from the first stage to the vacuum tube still heater, and passing 15 the withdrawn residuum through a separate heating coil, which may be located conveniently in the furnace of the first stage or topping tube still heater, and then introducing the heated residuum into the stripping tower. Preferably, connections are provided for selectively withdrawing 20 residuum from both the primary and stripping fractionating towers of the first stage, and for recycling the residuum through the separate heating coil and selectively returning to either or both 25 of the primary and stripping fractionating towers.

Referring to the drawing, in which the single figure is a diagrammatic illustration of apparatus for carrying out the method of the present invention, the first stage or topping tube still heater is indicated at 10. Oil to be distilled, such as crude oil, is drawn by pump 11 through pipe 12 and forced under pressure through heating coil 13 positioned within furnace 10. The heated oil is then passed by line 14 containing pressure release valve 15, and flashed at 16 into the primary fractionating tower 17. This tower may be of any suitable conventional construction for refluxing the vapors therein, as by reflux liquid introduced at 18. As shown, the tower is provided with a plurality of decks or bubble trays 19, one or more of which may be equipped with a liquid side stream withdrawal 20 controlled by valve 21. Uncondensed vapors pass overhead by line 22 to suitable condensers (not shown). 35

The side stream 20 is introduced at an intermediate point into the auxiliary or stripping tower 24, which is constructed with a plurality of bubble trays 25 above the zone of introduction of the side stream, and a plurality of staggered baffles 26 below this zone. One or more of the bubble trays 25 is equipped with a liquid side stream withdrawal 27 controlled by valve 28. 40

Residuum is withdrawn from tower 17 by line 30 controlled by valve 31, and from tower 24 by 55

line 32 controlled by valve 33. The residuums from the two towers are combined and drawn through pipe 34 by pump 35, which forces the residuum through line 36 controlled by valve 37 to a heating coil 38 positioned within the furnace of the second or vacuum stage tube still 39. The oil heated in this stage is then discharged through line 49 containing pressure release valve 41 into a vacuum fractionating tower 42 which 10 may be of conventional construction.

Positioned in advance of the second stage tube still 39 is a connection 44 controlled by valve 45, through which a portion of the combined residuum is withdrawn and passed to a heating coil 46 positioned within the furnace 10 of the first stage tube still heater. The coil 46 is preferably located within furnace 10 so that a regulation of the heating effect of the combustion gases may be obtained, such that an adequate control of the temperature of the heated oil is secured. The heated residuum is then discharged through line 47, and may be selectively introduced into the lower portion of the primary tower 17 by line 48 containing valve 49, or into the lower portion of the stripping tower 24 by line 50 containing valve 51. Line 50 preferably discharges into the stripping tower beneath the baffles 26, as indicated at 52, whereby the baffles serve as entrainment separators to remove heavy unvaporized oil 20 from the redistilled vapors passing upwardly through the stripping tower. Additional reflux may be introduced into the stripping tower by the line 53, and stripped vapors are returned to the primary tower through the vapor line 54.

35 In operation, crude oil is forced through heating coil 13 of the topping tube still and flashed at 16 into the primary fractionating tower. The lighter constituents including gasoline and kerosene fractions are primarily vaporized, and pass upwardly through the tower countercurrent to descending reflux liquid introduced at 18. Unvaporized liquid passes downwardly through the stripping section of the primary tower, and remaining lighter constituents are vaporized by 40 the heating effect of recycled residuum introduced by line 48. Gasoline may be removed overhead as vapor by line 22 to suitable condensers.

A kerosene fraction is condensed within the tower and removed at 20 as a side stream to the stripping tower 24. Here, the kerosene fraction is redistilled by the heating effect of recycled residuum introduced at 52. The kerosene vapors are freed of entrained heavy oil while passing around the entrainment separating baffles 26, 55 and are then refluxed and condensed in the bubble plate section 25 of the stripping tower by reflux introduced at 53. Retained gasoline constituents are effectively stripped and pass overhead by line 54 to the primary tower 17. A close cut kerosene fraction is removed by the side stream 27.

Residuums from both the primary tower 17 and the stripping tower 24 are removed by lines 30 and 32, and forced under pressure by pump 35 to lines 36 and 44. The proportion passing to the second stage tube still and the proportion recycled to the separate heating coil 46 are controlled by regulation of valves 37 and 45 respectively.

70 The recycled topped crude is heated in coil 46 to a temperature approximating the temperature of introduction of the original oil into the primary tower at 16, although this may be varied depending upon the character of distillation desired. For example, the original crude may be

heated in the coil 13 to a temperature of about 600°-650° F.; and the recycled residuum may be heated in the coil 46 to a temperature of around 625°-675° F. While the coil 46 is shown positioned in the furnace of the topping heater 10, it is to be understood that an entirely separate furnace may be employed for heating the said coil. By suitable control of the quantity of residuum recycled to both the primary and stripping towers 17 and 24, the use of stripping steam 10 may be entirely obviated. However, a proportion of steam may be admitted to the primary tower by the line 56, and to the stripping tower by the line 57, if desired. The installation provides for substantial flexibility of control, due to the independent control of the heating effect of the recycled residuum, the control of the proportion of residuum recycled, and the selective introduction of controlled proportions of reheated residuum into either the primary or stripping 20 towers, or both.

Obviously many modifications and variations of the invention, as hereinbefore set forth, may be made without departing from the spirit and scope thereof, and therefore only such limitations should be imposed as are indicated in the appended claims.

I claim:

1. In the non-cracking distillation of hydrocarbon oil, the method which comprises heating 30 the oil in a continuously flowing stream and flashing without any substantial cracking thereof into a primary fractionating zone of substantial fractionating capacity, refluxing the vapors therein, removing lighter vapors overhead to suitable condensers, withdrawing an intermediate distillate cut which is fractionated to a narrow cut, such as a kerosene fraction, as a side stream to a stripping fractionating zone of lesser fractionating capacity into which no cut lighter than 40 said intermediate distillate cut is introduced, withdrawing bottoms from the stripping fractionating zone, passing withdrawn bottoms in a continuously flowing stream through a heating zone, returning the heated bottoms to the stripping 45 fractionating zone to supply heat thereto to redistill the said side stream therein and separate it from entrained heavy oil and impurities, fractionating the vaporized side stream and condensing the same within the stripping fractionating 50 zone as a close distillate cut to separate it from retained lighter constituents, removing the said distillate cut as a side stream from an intermediate point of the stripping fractionating zone, and returning uncondensed vaporized lighter constituents from the stripping zone to the main fractionating zone.

2. In the non-cracking distillation of hydrocarbon oil, wherein the oil is heated in a continuously flowing stream and flashed without any substantial cracking thereof into a primary fractionating zone where the vapors are refluxed, and an intermediate distillate cut is removed as a side stream to a stripping fractionating zone; the method which comprises withdrawing bottoms from both the primary fractionating zone and the stripping fractionating zone, combining the bottoms and passing a portion thereof in a continuously flowing stream through a heating zone, returning the heated portion of the bottoms 70 to the stripping fractionating zone to supply heat thereto for stripping purposes, and removing a distillate cut as a side stream from an intermediate point of the stripping fractionating zone.

3. In the non-cracking distillation of hydro-

carbon oil, wherein the oil is heated in a continuously flowing stream and flashed without any substantial cracking thereof into a primary fractionating zone where the vapors are refluxed, and an intermediate distillate cut is removed as a side stream to a stripping fractionating zone; the method which comprises withdrawing bottoms from both the primary fractionating zone and the stripping fractionating zone, combining the withdrawn bottoms and passing a portion thereof in a continuously flowing stream through a heating zone, dividing the heated portion of the bottoms and returning a part thereof to the lower portion of the primary fractionating zone and another part thereof to the lower portion of the stripping fractionating zone, and removing a distillate cut as a side stream from an intermediate point of the stripping fractionating zone.

4. In the non-cracking distillation of hydrocarbon oil, the method which comprises heating the oil in a continuously flowing stream and flashing without any substantial cracking thereof into a primary fractionating zone of substantial fractionating capacity, refluxing the vapors therein, removing lighter vapors overhead to suitable condensers, withdrawing an intermediate distillate cut which is fractionated to a narrow cut, such as a kerosene fraction, as a side stream to a stripping fractionating zone of lesser fractionating capacity into which no cut lighter than said intermediate distillate cut is introduced, withdrawing bottoms from the primary fractionating zone, passing at least a portion thereof in a continuously flowing stream through a heating zone, introducing the heated bottoms into the lower portion of the stripping fractionating zone to redistill the said side stream therein and separate it from entrained heavy oil and impurities, fractionating the vaporized side stream and condensing the same within the stripping fractionating zone as a close distillate cut to separate it from retained lighter constituents, removing the said distillate cut as a side stream from an intermediate point of the stripping fractionating zone, and returning uncondensed vaporized lighter constituents from the stripping zone to the main fractionating zone.

5. In the two-stage non-cracking distillation of hydrocarbon oil, in which the oil is heated in the first stage in a continuously flowing stream and flashed into a primary fractionating zone, from which residuum is removed and passed in a continuously flowing stream through a second stage heater and then flashed into a vacuum fractionating zone; the method which comprises withdrawing a portion of the residuum from the first stage before it has passed through the second stage heater, passing the residuum thus withdrawn in a continuously flowing stream through a separate heating coil to provide an independent control of the temperature thereof, and returning the said heated residuum to the primary fractionating zone of the first stage to supply heat for stripping purposes therein.

6. In the two-stage non-cracking distillation of hydrocarbon oil, in which the oil is heated in the first stage in a continuously flowing stream and flashed into a primary fractionating zone, from which an intermediate distillate cut is removed as a side stream to a stripping fractionating zone, and residuum is removed and passed in a continuously flowing stream through a second stage heater and then flashed into a vacuum fractionating zone; the method which comprises returning heated residuum to the lower portion

of the stripping fractionating zone to supply heat thereto for stripping purposes.

7. In the two-stage non-cracking distillation of hydrocarbon oil, in which the oil is heated in the first stage in a continuously flowing stream and flashed into a primary fractionating zone, from which an intermediate distillate cut is removed as a side stream to a stripping fractionating zone, and residuum is removed and passed in a continuously flowing stream through a second stage heater and then flashed into a vacuum fractionating zone; the method which comprises withdrawing a portion of the residuum from the first stage and passing it in a continuously flowing stream through a separate heating coil to provide an independent control of the temperature thereof, and introducing the heated residuum to the lower portion of the stripping fractionating zone to supply heat for stripping purposes therein.

8. In the two-stage non-cracking distillation of hydrocarbon oil, in which the oil is heated in the first stage in a continuously flowing stream and flashed into a primary fractionating zone, from which a distillate cut is removed as a side stream to a stripping fractionating zone, and residuum is withdrawn from both the primary fractionating zone and the stripping fractionating zone and combined and passed in a continuously flowing stream through a second stage heater and then flashed into a vacuum fractionating zone; the method which comprises withdrawing a portion of the combined residuum from the first stage before it has passed through the second stage heater, passing the residuum thus withdrawn in a continuously flowing stream through a separate heating coil to provide an independent control of the temperature thereof, and introducing residuum thus heated to the lower portion of the stripping fractionating zone to supply heat thereto for stripping purposes.

9. In the topping distillation of crude oil, in which the crude oil is heated in a continuously flowing stream and then flashed into a primary fractionating zone, wherein a gasoline fraction is removed overhead, a kerosene fraction is removed as a side stream to a stripping fractionating zone, and a heavier residuum is removed from the lower portion of the primary fractionating zone; the method of obtaining a close kerosene cut which comprises passing a portion of the residuum in a continuously flowing stream through a heating zone and introducing the heated residuum into the lower portion of the stripping fractionating zone to supply heat thereto to vaporize a substantial portion of the said side stream therein, fractionating the vaporized side stream and condensing a major portion thereof within the stripping fractionating zone as a distillate kerosene cut, removing the said distillate kerosene cut as a side stream from the stripping fractionating zone, removing heavier oil as residuum from the stripping fractionating zone, and combining the heavier oil with the residuum from the primary fractionating zone.

10. In non-cracking distillation apparatus of the character described, the combination with a tube still heater flashing into a primary fractionating tower, a stripping tower, and a connection for withdrawing a distillate side stream from the primary tower and introducing it into the stripping tower; of connections for withdrawing residuum selectively from either or both of said towers, a heating coil, means for passing withdrawn residuum from either or both of said

- 11 - towers through said heating coil, connections for introducing the said heated residuum selectively to either or both of said towers, and means for withdrawing a side stream cut from said stripping tower.
11. In two stage non-cracking distillation apparatus of the character described, the combination with a first stage tube still heater flashing into a primary fractionating tower, a stripping tower, means for withdrawing a distillate side stream from the primary tower and introducing it into the stripping tower, a second stage tube still heater flashing into a vacuum fractionating tower, and means for passing residuum from the
- 10 15 first stage through the second stage tube still and thence into the vacuum tower; of a connection in advance of said second stage tube still heater for withdrawing a portion of the said residuum, a separate heating coil, means for passing the withdrawn residuum through said separate heating coil, a connection for introducing the heated residuum into the lower portion of said stripping tower, and means for withdrawing a side stream cut from said stripping tower.
- 15 20 25 30 35 12. In two stage atmospheric-vacuum non-cracking distillation apparatus of the character described, the combination with a tube still heater flashing into a primary atmospheric fractionating tower, a stripping tower, means for withdrawing a distillate side stream from the primary tower and introducing it into said stripping tower, a second stage tube still heater flashing into a vacuum fractionating tower, and means for passing residuum from said first stage through the second stage tube still heater and thence into the vacuum tower; of means in advance of said second stage tube still heater for withdrawing a portion of the residuum from said first stage, a

separate heating coil positioned within the first stage tube still heater, means for passing withdrawn residuum through said separate heating coil, connections for introducing the said heated residuum selectively into either or both of said primary and stripping fractionating towers, and means for withdrawing a side stream cut from said stripping tower.

13. In the non-cracking distillation of hydrocarbon oil, the method which comprises heating the oil in a continuously flowing stream and flashing without any substantial cracking thereof into a primary fractionating zone of substantial fractionating capacity, refluxing the vapors therein, removing lighter vapors overhead to suitable condensers, withdrawing an intermediate distillate cut which is fractionated to a narrow cut, such as a kerosene fraction, as a side stream to a stripping fractionating zone of lesser fractionating capacity into which no cut lighter than said intermediate distillate cut is introduced, supplying sufficient heat to the lower portion of the stripping fractionating zone to redistil the said side stream therein to separate it from entrained heavy oil and impurities, fractionating the vaporized side stream and condensing the same within the stripping fractionating zone to separate it from retained lighter constituents and produce a distillate cut closely controlled with respect to both its lower boiling and higher boiling ends, removing the said distillate cut as a side stream from an intermediate point of the stripping fractionating zone, and returning uncondensed vaporized lighter constituents from the stripping fractionating zone to the primary fractionating zone.

CECIL FERDINAND SLAWSON.
